UNITED STATES PATENT OFFICE.

WILLIAM PATON THOMSON, OF NEW YORK, N. Y., ASSIGNOR TO THE RAIL JOINT COMPANY, OF NEW YORK, N. Y., A CORPORATION OF NEW YORK.

RAIL-SPLICING STRUCTURE.

Application filed June 26, 1924. Serial No. 722,558.

This invention relates to a new type of rail joint, combining certain features of the head-free type rail joint of my Reissue Letters Patent No. 15,773 granted February 19, 5 1924 with supplementary features of construction producing a self-contained and highly resilient, yet powerful splicing structure.

The head-free type joint of my reissue 10 patent possesses the structural characteristic of having head clearance from the underside of the rail head and a loading engagement at the head fillet of the rail, utilizing in an advantageous manner the wedge formation 15 at the head fillet of the present standard rail whereby the head of the bar will have an upwardly and outwardly sliding bolt-tightening engagement with the rail head fillet. This head-free type rail joint bar may have 20 either direct or indirect solid engagement with the rail head fillet to bring the head of the bar into solid resistance to load deflections. These distinguishing and characterizing features of my patented structure referred to possess numerous practical advantages, and as far as possible, under certain 25 conditions, the present invention conserves many of these advantages in a structure wherein the end portions of the splice bars 30 will be caused to function in a different manner from their mid-sections, thus obtaining improved stability, absence of abrasive movement within the structure and protection of the rails from battering.

Accordingly, a primary object of the invention is to provide a splicing structure or rail joint having means whereby the medial portions of the splice bars will function in a manner substantially similar to the characteristic functioning of the splicing structure conforming to the reissue patent aforesaid. Furthermore, to provide means whereby the end portions of the splice bars will coact with the portion of the rail which is above 45 the boundary line between the surface of the rail web and the rail head fillet more directly or extensively than will the medial portion of the bar. Hence, the splice bar ends will coact with the upper portion of the rail web or the rail head fillet, or both, less directly or extensively than does the medial portion of the bar, even to the extent of not engaging these portions of the rail at all. These variant functions of the medial portions and of the end portions of the splice

bars, in the present invention, will so supplement each other as to enhance the rail alignment grip of the medial portions of the bars because the end portions of the bars may be so disposed with reference to the underside 60 of the rail heads as to provide practically any desired degree of resistance to displacement by vertically imposed load forces, even to the same degree as is characteristic of angle bars as generally used at the present 65 time.

Thus, it is proposed by the present invention to retain the basic principle involved in the invention of my former patent and to safeguard that principle by supplementing 70 additional stabilizing and stressing features of such a nature that the predominant characteristic of my former invention will be rendered more efficient throughout the mid-section of the splice bars by relieving that 75 section of the necessity of withstanding all of the upright and transverse load strains.

With these and various other objects in view which will be apparent to those familiar with this art as the nature of the invention is better understood, the same consists in the novel combination of features of construction hereinafter more fully described, illustrated and claimed; and while susceptible 80 of a wide range of structural modification 85 without departing from the spirit or scope thereof certain practical forms of the invention are shown in the accompanying drawings, in which:—

Figure 1 is a side elevation of a rail splicing structure embodying the present invention. 90

Figure 2 is an end view taken on the line 2—2 of Fig. 1, the full lines in the view showing the splice bar having head and foot bearings and the dotted lines showing the position of the bar at the center of the joint. 95

Figure 3 is a cross-sectional view of the joint on the line 3—3 of Fig. 1, showing respectively by full and dotted lines positions 100 of the splice bar at the center and at the ends of the joint.

Figure 4 is a detail elevation of one form of bearing member or plate that may be used to provide an indirect but solid bearing engagement between the splice bar and the rail web. 105

Figure 5 is a top edge view of the form of bearing member shown in Fig. 4.

Figure 6 is a reduced view similar to Fig. 110

1 showing how the invention may be carried out with a shortened bearing member; in this view part of the splice bar only being shown.

5 Figure 7 is a view similar to Fig. 1 illustrating the use of a modified construction of bearing plate to provide head fishing bearings for the ends of the bar and clearance of the medial portion of the bar from head fishing.

10 Figure 8 is a cross-section view on the line 8—8 of Fig. 7.

15 Figure 9 is a cross-sectional view on the line 9—9 of Fig. 7.

20 Figure 10 is a detail top plan view of the modified form of bearing plate shown in Figs. 7, 8 and 9.

25 It will now be seen that a principal feature of the present invention is to provide in a rail splicing structure or rail joint a splice bar having localized throughout the mid-section of its length a clearance from the underside of the rail head, while also having a solid bearing contact, either directly or 30 indirectly, with the rails above the center line of the bolt holes. That feature is combined with another principal feature, namely, that of the rail joint having localized at its end portions a splice bar having rail web clearance and a fishing engagement with the rail head and with the rail base flange. The said mid-section of the bar also has an engagement with the rail base flange.

35 These principal features of construction, in combination, provide means for holding the contiguous rail ends in true alignment and surface, and maintain the bolts effectively tightened. Specifically, it further 40 will be noted that the phase of the invention relating to resistance to vertically imposed loads is realized by so disposing the end portions of the splice bars that they will have an operative bearing engagement with 45 the fishing surfaces at the undersides of the heads of the rails, or upon the head fillets in conjunction with these fishing surfaces of a greater degree than is provided by the mid-sections of the splice bars. The effect 50 of this structure, under such conditions, is that the mid-sections of the splice bars will sustain the ends of the abutting or contiguous rails, both vertically and transversely, substantially in the manner provided for 55 by the head-free type joint of my reissue patent aforesaid, and the end portions of the splice bars can be made to supplement the mid-sections with whatever additional 60 resistance to vertically imposed load forces as may be necessary to meet the requirements of various types of rail, road-bed or bolting capacity. This delegation, to the portions 65 of the splice bar to which they are best adapted, of different functions to supplement each other in the manner described

will produce such an advantageous resultant of resistance to load strains as will stabilize the splice bars against displacement and wear more effectively, under certain conditions, than if any one of the differing functions were present throughout the whole length of each splice bar. As will be seen from the drawings, the end portions of each splice bar may be either flexed or shimmed into fishing engagement with the heads of the rails to be given such resistance to vertically imposed load forces as to be adequate to decrease materially the extent to which the mid-sections would otherwise have to be provided with means for resisting displacement under vertically imposed loads. And, the natural reactions of the mid-sections of the splice bars, when the preferable method of flexing the bars is resorted to, will be toward the webs of the rails and will thus supplement the function of the middle bolts to maintain the ends of the abutting rails firmly in true alignment.

30 The invention is well exemplified by the group of Figures 1 to 6 inclusive of the drawings. Referring thereto it will be seen that the splice bar employed may be and preferably is of uniform section throughout, so that the ordinary rolling mill product may be utilized in carrying forward the invention. This splice bar designated in the drawings by the reference letter S includes the usual head 1 and foot 2, the foot 2 of each splice bar being adapted to have a fishing engagement throughout as at 3 with the upper side of the base flange of the rail R. It is proposed by the present invention that the splice bar S shall have localized throughout the mid-section of its length, a clearance from the underside of the rail head as indicated by the numeral 4 in Fig. 3 of the drawings and as indicated by the dotted lines in Fig. 2 of the drawings. In connection with this clearance 4 of the mid-section of the splice bar from the underside of the rail head 5 the inner projection 6 of the splice bar head is adapted to have a bearing contact or engagement with the rails above the center lines of the bolt holes. This bearing contact for the inner head projection 6 of the mid-section of each splice bar may be direct or indirect, and preferably is localized at the head fillet of the rail so as to bring the head of the bar into solid resistance to load deflections, according to the principle involved in the invention of my reissue patent aforesaid. Preferably, the bearing contact or engagement for the inner head projection of the splice bar with the rail, at the medial portion of the head of the splice bar is provided for by utilizing a bearing member or plate 7 interposed between the splice bar and the rail. This bearing member or plate is preferably a mild steel plate which is thick enough to hold

the head of the splice bar, when loosely applied, out of contact with the outer portions of the overhanging sides of the rail heads and when the bolts are tightened and the 5 foot of the splice bar 2 is caused to move inwardly and upwardly on the rail base flange the head of the splice bar at the same time is caused to slide upwardly and outwardly, resulting in a bolt tightening action 10 and at the same time bringing the inner head projection of the splice bar into solid engagement, through the bearing member 7, with the rail head fillet whereby the head of the bar is properly positioned to 15 effectually resist load deflections. The wedge or tapered formation of the rail at the point where the upper part of the rail web merges into the rail head fillet compels the outward movement or deflection of the splice bar head 20 when forced upwardly by the bolt tightening action; and, in cases where the old type straight web rails may be encountered, the bearing members or plates 7 are shaped to give the taper corresponding to the wedge 25 formation referred to as found in present standard rails. This is a feature of the invention of my reissue patent aforesaid.

The bearing member of plate 7 may be of a depth, and preferably is, so that it may be 30 formed at its lower edges with keeper or holding notches 8 adapted to engage over the bolts and thus prevent longitudinal displacement of said member or plate, and, in the form of the invention now being described the said bearing member or plate 7 is of a shorter length than the splice bar and tapers in thickness toward its ends as at 9. This construction permits the ends 35 of the splice bars, when the bolts are tightened, to be forced or flexed toward the rails until they take a fishing engagement with the undersides of the rail heads, and at the same time will be clear of the rail webs. It is obvious that this flexing of the ends 40 of the splice bar which is permitted by the relatively shorter length of the bearing member 7 and the end taper of said member will supplement and enhance the clamping power exerted by the middle bolts upon the upper 45 portions of the rail webs. Not only will that desirable result be accomplished but the flexing of the splice bar ends also will react upon the nuts in such a manner as to decrease their liability to work loose, even 50 to the extent of eliminating any necessity for the use of nut locks.

It is to be understood that a splice bar could be so formed as to embody integrally 55 the characteristic features referred to, but that would be a difficult and expensive rolling proposition and it is preferable to carry forward the invention by using a splice bar of uniform section throughout and combining therewith a separate bearing member 60 or plate 7^a which may even be as short as

shown in the modification of Fig. 6 of the drawings. Also the various clearances and bearing engagements described may be provided for by using a special form of bearing member or plate, as for instance the 70 one illustrated in Figs. 7, 8, 9 and 10 of the drawings.

In the modification shown in the group of Figures 7 to 10 inclusive of the drawings the bearing member or plate therein is designated generally by the reference number 10 and in addition to having the keeper or holding notches 8^a previously referred to, is provided with a medial cut-away top portion 11 which provides a definite clearance 75 between the medial portion of the head of the splice bar and the underside of the rail head while leaving the apron or skirt of the bearing member in position to provide the solid bearing engagement for the medial 80 portion of the head of the splice bar with the rail in the region of the rail head fillet. Furthermore, this special form of bearing member or plate 10 is shown coextensive in length with the splice bar and is formed with top fishing members 12 having solid engagement with the underside of the rail head and with the upper side of the end portions of the head of the splice bar as plainly shown in Figs. 7 and 8 of the drawings. Also, the end portions of the skirt of the said special bearing member or plate 10 are shown cut-away as at 13 so as to leave clearance between the end portions of the head of the splice bar and the rail web 90 thereby providing for the same combination of functions for the mid and end sections of the splice bars, as heretofore explained.

From the foregoing it will now have been observed that an essential of the invention is that the medial portion of the head of the splice bar is never in operative contact with the outer portions of the undersides of the rail heads, which is a characteristic of the invention of my reissue patent aforesaid. 105 And, it should be understood that wherever reference herein is made to the medial portion, or mid-section, of one or both of the splice bars and a limited amount of rail head fishing bearing is mentioned, the rail head fillet which is the fillet that joins the surface of the rail web proper to the flat fishing surface of the rail head, as ordinarily prevailing in present practice, is not included in said limited amount of rail head 110 fishing bearing. Furthermore, when reference herein is made to the head of the medial portion of the splice bar as engaging or being in contact with any portion of the rail above the center lines of the bolt holes in the rail, such reference is intended to convey the meaning that either with or without a bearing member or element interposed between the rail and the splice bar head, a 115 solid medium is provided for transmission 120 of the load. 125

of the clamping capacity of the bolts, directly at or immediately adjacent to the juncture of the rail head with its web. However, a chief object of the utilization 5 of a separate bearing member, it will be noted, is to render the improvement broadly applicable to old splice bars either in service or in design, as well as to splice bars specially designed for adaptation for use 10 with the bearing member. And, it should also be noted that since the bearing member is constantly under compression, it may, advantageously, be of a metal having higher electrical conductivity than the splice bar 15 and utilized in an additional capacity as an electrical bonding element.

From the foregoing it is thought that the construction, functioning and many advantages of the herein described improvements 20 will be apparent without further description and it will also be understood that various changes in the form, proportion and minor details of construction may be resorted to without departing from the spirit 25 or sacrificing any of the advantages of the present invention.

I claim:

1. A rail joint including the rails, clamping bolts, a splice bar, and means for causing 30 the midsection of the splice bar to grip the ends of the rails above the bolt holes and to clear the underside of the rail head, and the end portions of the splice bar to grip the rail head and the rail base flange.

2. A rail joint structure for rails including 35 the splice bar, and a bearing member consisting of a metal plate or shim tapered toward both ends and interposed between the midsection of the splice bar and the rails.

3. A rail joint structure including the rails, and a splice bar which has, at its medial portion, a rail base fishing bearing and a head which has a solid engagement with 45 the rails above the bolt holes in the rails, said engagement being with the rail between the center line of the bolt holes in the rail and the inner boundary of the rail head fishing surface, and said splice bar 50 having, at its end portions, rail clearance from the region of the bolt holes to and including the rail head fillet, and means whereby the end portions of the splice bar may be so flexed that they will have rail 55 engagement above the boundary between the surface of the rail web and the rail head fillet.

4. A rail joint including the rails, and a splice bar having, at its medial portion, a rail base fishing engagement and a head 60 which has a rail engagement between the bolt holes and the inner boundary of the rail head fishing surface, and said splice bar having, at its end portions, a rail web 65 clearance, and means whereby the end por-

tions of said splice bar may be so flexed that they will have rail engagement above the boundary between the surface of the rail web and the rail head fillet.

5. A rail joint structure including the rails, 70 a bearing member contacting with a rail, and a splice bar contacting with said bearing member, said structure coacting, at the end portions of said splice bar, to grip the rail head and also coacting, at the medial 75 portion of said splice bar, to grip the rail base fishing bearings and the rail above the bolt holes inside of the inner boundary of the rail head fishing surface.

6. A rail joint structure including the 80 rails, a bearing member contacting with a rail, and a splice bar contacting with said bearing member, said structure coacting, at the medial portion of said splice bar, to engage the rail base fishing bearings and the 85 rails above the bolt holes but no more of a rail head than the under side of the inner portion of one of its overhanging sides, and said structure having, at its end portions, no initial engagement with the rails above the 90 bolt holes but having means whereby its end portions may be flexed so that they will have engagement with the rails above the bolt holes.

7. A rail joint including the rails, and a 95 splice bar having, at its end portions, rail base fishing engagement but no initial engagement with the rails above the bolt holes, and having, at its medial portion, rail base fishing engagement and engagement with the rails above the bolt holes but with no 100 more of a rail head than the under side of the inner portion of one of its overhanging sides, and means for flexing said end portions whereby they will have engagement 105 with the rails above the bolt holes.

8. A rail joint structure including the 110 rails, a bearing member contacting with a rail, and a splice bar contacting with said bearing member, said structure coacting, at the end portions of said splice bar, initially to engage rail base fishing bearings but no surface of a rail above the bolt holes, and also coacting, at the medial portion of said 115 splice bar, to engage the rail bases and the rails above the bolt holes but no more of a rail head than the under side of the inner portion of one of its overhanging sides.

9. A rail joint structure including the 120 rails, a bearing member engaging a rail, and a splice bar engaging said bearing member, said structure coacting, at the end portions of said splice bar, to engage the rail base but to initially engage no surface of a rail above the bolt holes, said structure having means 125 whereby said splice bar may be flexed so that its end portions will engage the rails above the bolt holes, and said structure also coacting, at the medial portion of said splice bar, to engage the rail bases and the rails, 130

above the bolt holes but no more of a rail head than the under side of the inner portion of one of its overhanging sides.

10. A rail joint structure including the rails, a splice bar, and a bearing member of greater electrical conductivity than said splice bar engaging the rails and the medial portion of said splice bar, said structure coating, at the medial portion of said splice bar, to engage the rail bases and the rails above the bolt holes and having rail head clearance, said splice bar also operating, at its end portions, initially to engage no surface of a rail above the bolt holes.
15. 11. A rail joint structure including the rails, a bearing member engaging the rails, and a splice bar engaging, at its medial portion, said bearing member, said structure coating, at the medial portion of said splice bar, to engage the rail bases and the rails above the bolt holes, said splice bar also operating, at its end portions, to engage initially no surface of a rail above the bolt holes, and means whereby said splice bar
20. 25. may be flexed so that its end portions will engage the rails at a higher point above the bolt holes than the rail engagement of said medial portion.
30. 12. A rail joint structure including the rails, a splice bar, and a bearing member of greater electrical conductivity than said splice bar engaging the rails and said splice

bar, said structure coating to engage the rail bases and the rails above the bolt holes but no more of a rail head than the under 35 side of the inner portion of one of its overhanging sides.

13. A rail joint including the rails, clamping bolts, a splice bar and a bearing member interposed between the inner part of the 40 head of the bar and the rail, and of shorter length than the splice bar, said splice bar having at its mid-section rail head clearance and having its ends flexed over the ends of the bearing member into rail head fishing 45 engagement.

14. A rail joint including the rail, clamping bolts, a bearing member and a splice bar having throughout its mid-section head clearance from the under side of the rail head and a loading engagement through said bearing member at the head fillet of the rail.

15. A rail joint including the rail, clamping bolts, a bearing member, and a splice bar having throughout its mid-section clearance 55 from the inside of the rail head and an inner head projection which has an upwardly and outwardly sliding bolt tightening engagement through said bearing member with the rail head fillet.

In testimony whereof I hereunto affix my signature.

WILLIAM PATON THOMSON.
